Inventor

John Kent David S. Williams

United States Patent Office.

DAVID S. WILLIAMS, OF COLDWATER, MICHIGAN.

Letters Patent No. 71,933, dated December 10, 1867.

IMPROVED BED-BOTTOM.

The Schedule referred to in these Letters Patent and making part of the same.

TO ALL WHOM IT MAY CONCERN:

Be it known that I, DAVID S. WILLIAMS, of the city of Coldwater, in the county of Branch, and State of Michigan, have invented a new and useful and improved Spring-Bed Bottom; and I hereby declare that the following is a full and exact description thereof, reference being had to the accompanying drawings.

The bedstead may be in any of the known forms and sizes.

Figure 1 of the drawings exhibits and represents the upper side of the bed-bottom complete, the slats, rods, India-rubber bands, leather fastenings, leather loops, and mode of fastening and suspension.

Figure 2, a transverse section or single slat, ends of rods, and mode of fastening to bedstead.

To enable others skilled in the art to make and use my invention and improvement, I will proceed to describe its construction and operation.

I use any of the known forms of bedstead-frames. I attach the loop A to the frame, in which I insert the rod B. The spring-band encircles the rods B and D. Webbing or equivalent, E, is used to fasten firmly the slats F. Loops or their equivalent, G, attach the slats F to the rods D.

A represents the leather loops; B, rods; C, India-rubber or other elastic spring-bands; D, rods; E, a webbing or other similar article; F, slats; G, wires, hooks, or leather loops; H, bedstead-frame.

What I claim as my invention, and desire to secure by Letters Patent, is—

The combination of the loop A, rods B, spring-band C, rods D, webbing E, slats F, wires or equivalent G, in the manner described.

D. S. WILLIAMS.
